UNITED STATES PATENT OFFICE

BENJAMIN H. WOODS, OF GASTONIA, NORTH CAROLINA

HEN'S NEST

Application filed May 21, 1930. Serial No. 454,467.

The object of the invention is to provide a hen's nest which may consist of any desired number of separable units each embodying a variable number of boxes or compartments adapted for use as nesting spaces for fowl, which may be constructed in knock down form for assemblage and disassemblage to facilitate thorough cleansing and sterilization as well as simplify shipment and storage, and which when set up or assembled may have a practical stability adapted to withstand the strains incident to the joint accommodation of a plurality of fowls, and with this general idea in view the invention consists in the combination and arrangement of parts of which the preferred embodiment is illustrated in the accompanying drawings wherein.

Figure 1 is a perspective view of a series of tiers of hens' nests embodying the invention;

Figure 2 is a vertical sectional view taken transversely;

Figure 3 is a detail perspective view of one end of the frame upon which the nest units are assembled;

Figure 4 is a similar view of one end of an intermediate nest; and

Figure 5 is a similar view of one end of the upper or topmost nest unit.

The device embodies essentially a frame comprising the horizontally disposed base or floor 10 and back 11, on which the former may be supported in spaced relation with the hen house floor or like object by means of the depending legs or feet 12 and one or more nest units comprising in the construction illustrated the intermediate nest units 13 and 14 and the top nest unit 15, corresponding essentially in construction and adapted to be arranged in tiered or successively superposed relation with the lower or intermediate nest resting upon and supported by the base or floor of the frame. Each of these units embodies one or more nest boxes, a plurality of which are illustrated in the device shown in the drawings, so that each nest unit consists of a plurality of series of nest boxes removable from and applicable to the frame as a unit, and each unit having nest box side

walls 13a, 14a, etc. and a top wall or cover 13b, 13b, etc.

The front, bottom and rear of each nest box is open so that when the lowermost unit is placed upon the frame the bottom of the nest boxes comprising said unit are formed by the base or floor of the frame, while the rear wall of the nest boxes comprising said unit are formed by the rear wall 11 of said frame. The same is true of the superposed units to any number which may be desired by the builder or required by the number of fowls to be accommodated, with the exception that the uppermost unit of which the nest box side walls are shown at 15a has a top wall 15b which is pitched or inclined to prevent its use as a roost, as illustrated in the drawings. A supplemental cover and unit locking means 15c is hinged and detachably mounted by means of hinges 16 upon the upper edge of the rear wall 11 of the frame, to overlie the top wall of the uppermost unit and is preferably disposed at an inclination downwardly and forwardly to constitute a water shed. This cover is secured at its front edge by latches 15d and serve to lock the elements of the structure in their operative relations.

At the front of each of the units with the exception of the lowermost (which rest directly on the frame) there is arranged a platform or perch for use by the fowls in entering and leaving the nest boxes, and at the bottom of the lowermost unit or tier of boxes there is also a platform for use in connection with that tier, the platform for the lowermost unit which is indicated at 17, consisting of a forward extension of the floor or bottom of the frame, while the platforms or perches 18 of the superposed units are formed by forward extensions of the top walls of the intermediate units suitably braced by brackets 19 formed by the forward continuation of the side walls of the nest boxes. Moreover, as a means of preventing displacement or disarrangement of the units of the assembled structure an interlocking engagement is established between the units as by forming at the front edges thereof depending webs 20 for engagement with the seats 100

21 formed in the floor or bottom of the frame by a spaced relation between the floor or bottom proper and the extension 17, and on the units by a similar separation between the upper wall of the unit and the extension which constitutes the platform or perch. When the parts are assembled, therefore, the parts 20 drop into the seats 21 and hold the rear edges of the side walls of the nest boxes in contact with the front surface of the rear wall 11 of the frame while permitting the ready displacement or disassembling of the elements to give free access to the interiors of the nest boxes for the purpose of cleaning, sterilizing, and disinfecting.

In practice, it is desirable to employ means for holding a suitable amount of straw or bedding in each unit box for the convenience and comfort of the fowl and to this end a straw guard consisting of a strip 23 is arranged transversely in spanning relation with the front of each nest box at its bottom and in practice the strip which forms this straw guard in relation to each unit may be extended downwardly as shown in the drawings, below the lower edges of the nest boxes to constitute the rib 20 forming a portion of the interlocking means by which the units are held in their proper positions.

30 What is claimed is:

1. A knockdown hen's nest having a frame comprising a floor and a back, and nest units each having end walls, a top wall and intermediate walls dividing the units into nest compartments, each of said compartments being open at the front and rear and at the bottom, said units being arranged in superimposed tiered and interlocked relation to each other upon said frame.

40 2. A knockdown hen's nest having a frame comprising a floor and a back, and nest units each having end walls, a top wall and intermediate walls dividing the unit into nest compartments, said units being arranged in superimposed tiered relation upon said floor, said compartments being open at the front and rear and at the bottom thereof, the top walls of the intermediate units forming floors for the units thereabove and being extended beyond the plane of the front of the units to form platforms or perches.

50 3. A knockdown hen's nest having a frame comprising a floor and a back, and nest units each having end walls, a top wall, and intermediate walls dividing the unit into nest compartments, said compartments being open at the front and rear and at the bottom thereof and arranged in superimposed tiered relation upon said floor and in position to have their rear openings closed by said back, and a cover hinged to said back and overlying the uppermost unit.

60 4. A knockdown hen's nest having a frame comprising a floor and an upright back, and a plurality of nest units each having end

walls, a top, and intermediate walls dividing the unit into nest compartments, a guard wall connecting the lower portions of the end and intermediate walls whereby to partially close the front openings of the compartments, said compartments being open at the rear and at the bottom thereof, said units being arranged in superimposed and interlocked relation upon said floor and having their rear openings closed by said back, and means movably mounted on said back and engaging with the uppermost of said units for holding said units in place.

5 5. A knockdown hen's nest having a frame comprising a floor and a vertical back mounted thereon, nest units each having end walls, a top wall, and intermediate walls dividing the units into compartments, a straw guard wall extending longitudinally of a unit and connected to the lower portions of the front edges of said end and intermediate walls, said guard wall having its lower edge extending below the last-named walls, said units having front and rear openings and a bottom opening and being arranged in superimposed relation to each other upon said floor, the top walls of the intermediate units forming the floors of the units thereabove and extending outwardly beyond the fronts of the units to form platforms, each of said platforms having a longitudinal groove receiving the lower edge of a guard wall, said back closing said rear openings, and means on said back engaging the uppermost of the units for holding the units on said frame.

6. A knockdown hen's nest having a supporting frame including a floor and a vertical back mounted thereon, nest units each comprising end walls, a top wall, and intermediate walls dividing the unit into nest compartments, each of said compartments having a front opening, a rear opening, and a bottom opening, a straw guard wall extending longitudinally of the unit and closing the lower portions of said front openings, said guard wall extending below said end and intermediate walls, the top wall of each of the intermediate units extending outwardly beyond the front of the units to form a platform, said platform being separated from the remainder thereof by a groove, said groove receiving the lower portion of said guard wall of the unit above, and a hinged member carried by said back and resting on the uppermost of the units for holding the latter in place on said frame.

In testimony whereof, I affix my signature.
BENJAMIN H. WOODS.
